Primary Examiner — Richelle G Shelton(74) *Attorney, Agent, or Firm* — Nixon & Vanderhye P.C.(57) **CLAIM**

The ornamental design for a cushion for respiratory mask, as shown and described.

DESCRIPTION

FIG. 1 is a front perspective view of a cushion for respiratory mask according to our new ornamental design;

FIG. 2 is a front view thereof;

FIG. 3 is a rear view thereof;

FIG. 4 is a top view thereof;

FIG. 5 is a bottom view thereof;

FIG. 6 is a right side view thereof, with the left side view thereof being a mirror image thereof; and,

FIG. 7 is a reverse perspective view thereof.

The broken lines represent environmental structure and do not form a part of the claimed design.

1 Claim, 5 Drawing Sheets(56)
